GEORGE T. PEARSONS, OF NEW YORK, N. Y.

FIRE-EXTINGUISHER.

1,388,883.

Specification of Letters Patent. Patented Aug. 30, 1921.

Application filed September 27, 1916. Serial No. 122,324.

To all whom it may concern:

Be it known that I, GEORGE T. PEARSONS, a citizen of the United States, residing in the borough of Manhattan, in the city, 5 county, and State of New York, have invented new and useful Improvements in Fire-Extinguishers, of which the following is a specification.

This invention relates to fire extinguishers of the syringe type in which a reservoir is provided with a fire extinguishing liquid, such as carbon tetrachlorid, or a composition of which carbon tetrachlorid forms a component part, and which liquid is ejected 10 from the reservoir by pumping mechanism within the reservoir, and it is the primary object of the invention to improve the general construction of extinguishers of this type to increase the efficiency thereof.

In syringes of this type having a double acting pumping mechanism as the piston reaches the end of its outward and inward strokes and the motion of the piston is reversed there is a break in the ejected stream 15 due to the relieving of the pressure by the piston in the pumping cylinder and the breaking of the suction. The stream ejected from the syringe must of necessity be relatively small and it has been found that due 20 to this intermittent breaking of the stream the force of the ejected stream is materially reduced with the result that when the force of the stream is again increased due to the movement of the piston the stream will not 25 penetrate the wall of heat around a fire, and this is especially so should the intensity of 30 this heat wall be increased due to the spreading of a fire, with the result that the efficiency of a syringe as a fire extinguisher is 35 greatly impaired. It is an object of the 40 present invention to overcome this disadvantage and provide an improved syringe in which the liquid being ejected is at all times 45 under pressure and forcibly ejected with no 50 breaks in and a consequent reduction in the force of the stream at any time during the operation of the syringe, and for which purpose there is provided a compression chamber or chambers into which the liquid is dis-

provide improved means to connect the pumping mechanism with the liquid in the 55 lowermost part of the reservoir in all positions of the syringe.

In the drawing accompanying and forming a part of this specification Figure 1 is a longitudinal sectional view of a syringe 60 illustrating an embodiment of my invention.

Fig. 2 is a cross section taken on the line 2—2 of Fig. 1 looking in the direction of the arrows; and

Fig. 3 is a detail view in perspective of 65 one of the members to lock the piston rod in position with the piston in its innermost position.

Similar characters of reference designate 70 like parts throughout the different views of the drawing.

In the embodiment of my invention shown in the drawing there is provided a reservoir for a fire extinguishing liquid consisting of a tubular body portion 4 to which are secured the ends 5 and 5', said reservoir having a filler opening closed by a plug 6 having a spring influenced check valve opening into and closing outward from the reservoir. The body portion has a contracted 75 portion extending longitudinally thereof, as at 7, to constitute a pump carrying chamber and the large portion of the reservoir constituting a liquid carrying chamber, thus providing the reservoir with integral pump 80 carrying and liquid carrying chambers.

A piston chamber is located in the contracted portion of the reservoir consisting of a pair of heads 8 and 9, one head to lie contiguous to each end of the reservoir, and 90 a cylinder 10 connected at opposite ends to said heads. The head 8 has a part to engage in an opening in the reservoir end 5, as at 11, and the head 9 has a cylindrical portion or sleeve 12 extending through an opening 95 in the reservoir end 5', and the pump chamber is fixed in position in the reservoir by soldering the head projections 11 and 12 to the reservoir. Each of the heads 8 and 9 has a projection 13, 14 extending laterally into 100 the liquid carrying chamber with ports 15, 16 in said head extensions to opposite ends of the cylinder 10, the ports having inlets 17, 18 in a part of said head extensions coaxial with the axis of the liquid carrying chamber. 105 for a purpose to be hereinafter described.

A further object of the invention is to

The piston chamber has an outlet 19 in the head 8 communicating with a casing 20, which is in the nature of a compression chamber, and the latter chamber has an outlet 21 in the head 8 to the exterior of the reservoir.

A piston 22 having suitable packing is reciprocable in the piston chamber by a hollow piston rod 23 extending through the head 9 and packing 24 retained in the sleeve portion 12 by a nut 25 to form a stuffing box and seal the piston rod, and the rod has an operating handle 26 fixed thereto. The piston rod has ports 27 adjacent its inner end and the piston has free movement on the piston rod during the initial portion of its outward and inward movements between a pair of abutments 28, 29 fixed on the piston rod to control the opening and closing of the piston rod ports. A tube 30 is fixed at one end in the head 8 and extends into the piston rod to adjacent the opposite or beyond the opposite head 9, said tube being of less diameter than the piston rod to provide a space between the two and with which tube the piston rod has a telescoping movement.

To connect the piston chamber with the outlet 19 of the piston chamber and the compression chamber 20 there is fixed in the outlet 19 a second tube 31, said tube extending into the tube 30 to a point substantially midway the length thereof and is of less diameter than the tube 30 to provide a space between the two and thus providing an air compression chamber within the tube 30.

To shut off communication between the tube 30 and the piston chamber, and thereby the reservoir, to prevent leakage and evaporation of the liquid when the syringe is not in use the handle has in a recessed portion 32 therein a valve to engage with and close the end of the tube 30 when the piston is in its innermost position. This valve consists of a disk 33 of suitable material, such as cork, secured in a carrier 34 slidably mounted in the handle recess 32 and normally engages with an annular flange at the opening to the recess 32 by a spring 35. To forcibly retain the valve in engagement with the end of tube 30 and lock the piston in its innermost position the piston rod has a projection 36 which is adapted to pass through a slot 37 (Fig. 3) in a member 38 engaging in and having a threaded connection with a tubular extension 39 on the nut 25, and the projection engaging with an inclined or cam face 40 at the inner end of said member. The outlet 21 preferably is tapered as shown and has a tube 41 fixed therein to extend into the compression chamber 20.

To connect the piston chamber with the liquid in the lowermost part of the reservoir in all positions of the syringe a tube 42 is connected at opposite ends with the inlets

17 and 18 to the ports of the piston chamber and has a series of circumferentially disposed ports 43 at a point between its ends, preferably centrally. A second tube 44 extending longitudinally of the liquid carrying chamber with its ends adjacent the side and opposite ends of said chamber is connected to the tube 42 through the ports 43 by coupling 45 through which the tube 42 extends, the coupling being mounted upon the tube 42 to permit said coupling with the tube 44 to revolve about the tube 42 as an axis, and whereby the tube 44 is adapted to revolve in the liquid carrying chamber on an axis in line with the axis of said chamber. To prevent endwise movement of the coupling a pair of collars 46, 47 are fixed on the tube 42 with felt or fiber washers interposed between the ends of the coupling and said collars.

To shut off communication between one end of the tube 44 and the reservoir when the other end of the tube is connected to the reservoir, as, for instance, to connect the end of the tube adjacent the end of the reservoir with the piston operating handle and shut off the opposite ends when the syringe is held in position with the outlet end of the piston chamber tilted upward from the horizontal, a pair of valves are provided to coöperate with valve 49 seats connected to or formed in the ends of the tube 44, said valves being connected by a rod 50 extending through and of greater length than the tube 44. The inlets to ports 15 and 16 are provided with check valves 15' and 16' opening into and closing outward from the piston chamber.

The operation is substantially as follows, assuming the parts to be in the position shown in Fig. 1 with the piston rod locked in position with the valve 33 engaging with and closing the end of tube 34. The piston is first given a partial rotation to cause the projection 36 to register with the slot 37 in the locking member 38 when the piston rod is drawn outward and with it the piston, the piston during the initial movement of the rod having a slight movement thereon until it engages with the abutment 28 thereby connecting the piston chamber in back of the piston with the piston rod through the rod ports 27 and forcing the liquid in the piston chamber in back of the piston into the piston rod and into the tube 30, and from said tube through the tube 31 into the compression chamber 20 and from the latter through the outlet 21. The piston during this outward movement draws in liquid into the piston chamber in front of the piston through the suction inlet 15. During the initial portion of the inward movement of the piston rod the piston also has a slight free movement on the piston rod until it engages with the abutment 29 uncovering 130

the piston rod ports in front of the piston and thereby connecting the piston chamber in front of the piston with the piston rod, the liquid previously drawn into the piston 5 chamber in front of the piston on the inward movement of the piston rod being forced through the piston rod ports into the piston rod and through the tubes 30, 31 into chamber 20 and out through the outlet 10 21, the piston during this inward movement drawing liquid into the piston chamber in back of the piston through the suction inlet 16, when the operation is repeated during the reciprocation of the piston. It will 15 be noted that the piston divides the piston cylinder into two chambers each of which chambers has a suction inlet connected to the reservoir and which chambers are alternately connected with the outlet of the piston 20 cylinder through the piston rod, tubes 30, 31 and the compression chamber formed therein, and through the compression chamber 20. During the discharging of the liquid with the discharge end of the piston chamber 25 tilted upward from the horizontal air will be pocketed between the tubes 30, 31, the said space between the tubes forming a compression chamber in which the air is compressed by the liquid in the tube 30 adjacent 30 the open end of tube 31, and which air will serve to eject the liquid from the tube 30 at all times, and especially during the time that the movement of the piston is reversed with the result that a steady stream of 35 substantially the same force is ejected at all times during the pumping operation. Should the discharge end of the piston chamber be tilted downward from the horizontal the liquid in the chamber 20 will 40 pocket and compress the air in the end of the chamber opposite to the outlet 21 with the result that said air will also serve to eject the liquid in a steady stream at all times during the operation of the pumping 45 mechanism.

Having thus described my invention, I claim:

1. In a syringe the combination of a reservoir; a piston cylinder therein; a piston to reciprocate in said cylinder; a hollow piston rod, said rod and piston being arranged to discharge the liquid from the piston cylinder at opposite sides of the piston into the piston rod; a tube in the piston rod through 50 which to discharge the liquid from the piston rod; and a chamber to which the tube is connected having an outlet to the exterior of the reservoir for the purpose specified.
2. In a syringe, the combination of a reservoir to contain liquid; a piston cylinder in said reservoir; a piston to reciprocate in said cylinder; a hollow piston rod extending from one end of the piston cylinder and reservoir, said rod having ports controlled 55 by the piston to connect the interior of the
3. In a syringe the combination of a reservoir having a discharge outlet; a piston cylinder in said reservoir; a piston to reciprocate in said cylinder; a hollow piston rod; a tube in the piston rod; and means to connect said tube with the discharge outlet and provide a chamber between said tube and the outlet, substantially as and for the purpose specified. 85
4. In a syringe the combination of a reservoir; a piston cylinder in said reservoir; a piston to reciprocate in said cylinder; a hollow piston rod; a fixed tube projecting into the piston rod; and means to connect said tube with the discharge outlet chamber and provide a compression chamber within the tube, substantially as and for the purpose specified. 90
5. In a syringe the combination of a reservoir; a piston cylinder in said reservoir connected adjacent opposite ends with the reservoir; a hollow piston rod having ports; a piston reciprocable by the rod in the piston chamber and operable to control the opening and closing of the piston rod ports to connect the piston rod with and discharge the liquid from said cylinder from opposite sides of the piston into the piston rod; a fixed tube extending into the piston rod; and means to connect said tube with the discharge outlet and provide chambers within the tube and between said means and the discharge outlet, substantially as and for the purpose specified. 95
6. In a syringe the combination of a reservoir; a piston cylinder in said reservoir connected adjacent opposite ends with the reservoir; a hollow piston rod having ports; a piston reciprocable by the rod in the piston cylinder and operable to control the opening and closing of the piston rod ports to connect the piston rod with and discharge the liquid from the piston cylinder from opposite sides of the piston into the piston rod; a fixed tube extending into the piston rod; a second tube extending into the first tube discharge outlet; and means to connect said tube with the discharge outlet and provide chambers within the first tube and between the second tube and the discharge outlet of the piston chamber, substantially as and for the purpose specified. 105
7. In a syringe the combination of a reservoir; a piston cylinder in said reservoir 110

- having suction inlets connected to the reservoir; a chamber at one end of said cylinder having an outlet to the exterior of the reservoir; a piston to reciprocate in the cylinder; a hollow piston rod; and means to connect the cylinder through the piston rod with the chamber at the end of the cylinder, substantially as and for the purpose specified.
- 10 8. In a syringe the combination of a reservoir; a piston cylinder in said reservoir having suction inlets connected to the reservoir; a chamber at one end of the cylinder having an outlet to the exterior of the reservoir; a hollow piston rod having ports extending from the cylinder end opposite to the end with the chamber; a tube connected to the chamber at one end of the cylinder and extending into the piston rod; and a piston reciprocable in the cylinder operable to control the opening and closing of the piston rod ports to connect the cylinder at opposite sides of the piston with the chamber at one end of the cylinder through the piston rod and tube, substantially as and for the purpose specified.
- 15 9. In a syringe the combination of a reservoir; a piston cylinder in said reservoir having a suction inlet connected to the reservoir; a chamber at one end of the cylinder having an outlet to the exterior of the reservoir; a hollow piston rod having ports extending from the end of the cylinder opposite to the end with the chamber; a tube connected to the inlet of the chamber and extending into the piston rod; a piston reciprocable in the cylinder operable to control the opening and closing of the piston rod ports to connect the cylinder at opposite sides of the piston with the chamber at one end of the cylinder through the piston rod and tubes; a valve carried by the piston rod to co-operate with the first tube to shut off communication between said tube and the cylinder when the piston is in its innermost position; and means carried by the piston rod and cylinder to lock the piston rod in position with the piston in its innermost position, substantially as and for the purpose specified.
- 20 10. In a syringe the combination with a reservoir; a piston chamber in said reservoir comprising a pair of heads to lie adjacent opposite ends of the reservoir and each head having a part to extend through openings in the reservoir ends, and a cylinder connected at its ends to the cylinder heads; suction inlets in the heads to the cylinder; a chamber in one head having an outlet to the exterior of the reservoir; a hollow piston rod having ports extending through the head opposite the head with the chamber; a tube connected to the chamber in the one head and extending into the piston rod; and a reciprocable piston operable to draw liquid from the reservoir to the cylinder at opposite sides of the piston and control the opening and closing of the piston rod ports to alternately connect the chamber in the one head with the cylinder at opposite sides of the piston, substantially as and for the purpose specified.
- 25 11. In a syringe the combination with a reservoir; a piston chamber located adjacent the side wall of the reservoir comprising a pair of heads one head to lie contiguous to each end of the reservoir, and a cylinder connected at opposite ends to said heads,

and tube, substantially as and for the purpose specified.

12. In a syringe the combination of a reservoir; a piston cylinder in said reservoir having suction inlets connected to the reservoir; means connected to the suction inlets to connect the cylinder with the liquid in the lowermost part of the reservoir in all positions of the syringe; a chamber at one end of the cylinder having an outlet to the exterior of the reservoir; a hollow piston rod having ports extending from the end of the cylinder opposite to the end with the chamber; an operating handle connected to said extending end of the piston rod; a fixed tube extending from the end of the cylinder with the chamber to adjacent the operating handle of the piston rod; a second tube connected to the chamber at one end of the cylinder and extending into the first tube to connect the latter with said chamber and provide a compression chamber therein; a piston reciprocable in the cylinder operable to control the opening and closing of the piston rod ports to connect the cylinder at opposite sides of the piston with the chamber at one end of the cylinder through the piston rod and tubes; a valve carried by the piston rod to co-operate with the first tube to shut off communication between said tube and the cylinder when the piston is in its innermost position; and means carried by the piston rod and cylinder to lock the piston rod in position with the piston in its innermost position, substantially as and for the purpose specified.

13. In a syringe the combination with a reservoir; a piston chamber in said reservoir comprising a pair of heads to lie adjacent opposite ends of the reservoir and each head having a part to extend through openings in the reservoir ends, and a cylinder connected at its ends to the cylinder heads; suction inlets in the heads to the cylinder; a chamber in one head having an outlet to the exterior of the reservoir; a hollow piston rod having ports extending through the head opposite the head with the chamber; a tube connected to the chamber in the one head and extending into the piston rod; and a reciprocable piston operable to draw liquid from the reservoir to the cylinder at opposite sides of the piston and control the opening and closing of the piston rod ports to alternately connect the chamber in the one head with the cylinder at opposite sides of the piston, substantially as and for the purpose specified.

14. In a syringe the combination of a reservoir; a piston chamber located adjacent the side wall of the reservoir comprising a pair of heads one head to lie contiguous to each end of the reservoir, and a cylinder connected at opposite ends to said heads,

- each of the heads having a part extending laterally into the reservoir; ports in said head extensions communicating with opposite ends of the cylinder and having inlets 5 extending in line with the axis of the reservoir; an outlet in one of said heads to the exterior of the reservoir; a piston in the cylinder to separate the cylinder into two chambers; a hollow piston rod to reciprocate 10 the piston; and means to alternately connect the chambers at opposite sides of the piston with the outlet through the piston rod, substantially as and for the purpose specified.
14. In a syringe the combination of a reservoir; a piston chamber in the reservoir located adjacent the side thereof comprising a pair of heads one head to lie contiguous to each end of the reservoir, and a 15 cylinder connected at opposite ends with the heads, each of the heads having a part extending laterally into the reservoir; ports in said head extensions communicating with opposite ends of the cylinder and having inlets 20 to extend in line with the axis of the reservoir; an outlet in one of said heads to the exterior of the reservoir; a tube extending longitudinally of the liquid carrying chamber rotatably connected to the inlets 25 of the ports in the head extensions and revoluble on an axis in line with said ports; and piston mechanism to draw liquid from the reservoir to the piston chamber at opposite sides of the piston and discharge said 30 liquid through the outlet in the one head of the piston chamber, substantially as and for the purpose specified.
15. In a syringe the combination of a reservoir; a piston chamber in the reservoir 35 located adjacent the side wall comprising a pair of heads one head to lie contiguous to each end of the reservoir, and a cylinder connected at opposite ends to the heads, each of the heads having a part to extend laterally into the reservoir; suction inlets in said head extensions to opposite ends of the cylinder; an outlet in one of said heads to the exterior of the reservoir; a piston to reciprocate in the cylinder; a hollow piston 40 rod to extend through the head opposite to the head having the outlet; a tube connected to the outlet extending into the piston rod to adjacent the other end of the cylinder; and valve mechanism to control the entrance 45 of liquid from the reservoir to the piston chamber at opposite sides of the piston and the ejecting of said liquid alternately from opposite ends of the piston, substantially as and for the purpose specified.
16. In a syringe the combination of a reservoir; a piston chamber in the reservoir 50 located adjacent the side wall comprising a pair of heads one head to lie contiguous to each end of the reservoir, and a cylinder connected at opposite ends to the heads, each of the heads having a part extending laterally into the reservoir; ports in said head extensions communicating with opposite ends of the cylinder and having inlets 55 extending in line with the axis of the reservoir; an outlet in one of the heads for the cylinder to the exterior of the reservoir; a tube connected at opposite ends to the inlets of the ports and having circumferentially disposed apertures at a point between its ends; an intake tube extending longitudinally of the reservoir with its ends adjacent the side and opposite ends of said chamber; and means to revolubly support said tube on the first tube and connect it with the circumferentially disposed apertures therein, 60 substantially as and for the purpose specified.
17. In a syringe the combination of a reservoir; a piston chamber in the reservoir located adjacent the side wall comprising a pair of heads one head to lie contiguous to each end of the reservoir, and a cylinder connected at opposite ends to the heads, each of the heads having a part to extend laterally into the reservoir; suction inlets in said head extensions to opposite ends of the cylinder; an outlet in one of said heads to the exterior of the reservoir; a piston to reciprocate in the cylinder; a hollow piston rod to extend through the head opposite to the head having the outlet; a tube connected to the outlet extending into the piston rod to adjacent the other end of the cylinder; and valve mechanism to control the entrance of liquid from the reservoir to the piston chamber at opposite sides of the piston and the ejecting of said liquid alternately from opposite ends of the piston, substantially as and for the purpose specified.
18. In a syringe the combination of a reservoir; a piston chamber therein fixed at opposite ends to the reservoir and having suction inlets at opposite ends connected to the reservoir; a casing at one end of said chamber with an outlet to the exterior of the reservoir; a piston to reciprocate in the piston chamber; a hollow piston rod extending from the end of the piston opposite to the casing; a tube connected at one end to the casing and extending into the piston chamber; and valve mechanism operable during the reciprocation of the piston to control the flow of liquid from the reservoir to the piston chamber at opposite sides of the piston and the ejecting of the liquid alternately from opposite sides of the piston into the casing, substantially as and for the purpose specified.
19. In a syringe the combination of a piston cylinder having suction inlets adjacent opposite ends and an outlet at one end; a hollow piston rod having ports extending from the end of the cylinder opposite to the outlet; an operating handle connected to the piston rod, substantially as and for the purpose specified.

said extending end; a fixed tube extending into the piston rod from the end of the cylinder opposite to the operating handle; a piston to reciprocate in the cylinder and control the opening and closing of the piston rod ports to connect the piston rod with the cylinder at opposite sides of the piston;

means to connect the piston rod with the cylinder outlet and provide a compression chamber in the fixed tube; and a reservoir 10 in which the cylinder is fixed at opposite ends, substantially as and for the purpose specified.

GEO. T. PEARSONS.
